Primary Examiner — Mark A Goodwin*Assistant Examiner* — Benjamin M Weeks(74) *Attorney, Agent, or Firm* — Birch, Stewart, Kolasch & Birch LLP(57) **CLAIM**

The ornamental design for a headlight for motorcycle, as shown and described.

DESCRIPTION

FIG. 1 is a front left perspective view of a headlight for motorcycle.

FIG. 2 is a front right perspective view thereof.

FIG. 3 is a front elevation view thereof.

FIG. 4 is a left side elevation view thereof.

FIG. 5 is a right side elevation view thereof; and,

FIG. 6 is a top plan view thereof.

The broken lines shown in the drawings illustrate portions of the headlight for motorcycle that form no part of the claimed design.
